UNITED STATES PATENT OFFICE.

ROBERT L. WELCH, OF CHICAGO, ILLINOIS, ASSIGNOR TO A. G. SPALDING & BROS., OF NEW YORK, N. Y., A CORPORATION OF NEW JERSEY.

BASE-BALL MASK.

1,081,793.

Specification of Letters Patent. Patented Dec. 16, 1913.

Application filed July 1, 1913. Serial No. 776,760.

To all whom it may concern:

Be it known that I, ROBERT L. WELCH, a citizen of the United States, residing in the city of Chicago, in the county of Cook, in the State of Illinois, have invented certain new and useful Improvements in Base-Ball Masks, of which the following is a specification, reference being had to the accompanying drawings, forming a part hereof.

10 This invention relates to baseball masks for catchers and has for its object to improve their construction by affording greater protection to the wearer than formerly, rendering their use more convenient to the wearer, strengthening their construction and generally improving their appearance.

One of the principal objects is to provide suitable protection for the ears of the catcher by mounting on opposite sides of the main frame of the mask at the proper points additional protecting frames. In realizing this object of the invention the ear protecting frames are so united to the other main frame of the mask as to reinforce the latter 25 and render the entire mask more substantial than in previous constructions.

Another object is to eliminate the inconvenience so often encountered by catchers who are tobacco chewers and find it necessary to expectorate frequently. This object is attained by providing in the front protecting frame work of the mask a suitable free space disposed opposite the mouth of the catcher to permit free expectoration.

35 Still a further object of the invention is to provide improved means for securing the usual center head strap of the mask to the frame.

In furtherance of the general object of 40 improving the appearance of the mask, the usual clear vision construction is attained by forming the upper eye wire substantially straight, while the lower eye wire is curved downwardly opposite the eyes of the catcher.

45 The invention will be more particularly described hereinafter, reference now being had to the accompanying drawings for a detailed description thereof.

In these drawings—Figure 1 is a view in 50 front elevation of a mask embodying the present invention. Fig. 2 is a view in side elevation thereof.

The main outer frame of the mask is composed of suitable stout wires *a* and *a'* to 55 which may be welded or otherwise secured

additional wires *b* extending in diverse directions and so interconnected as to constitute a suitable protection for the face of the catcher. Suitable padding *a²* may be secured around the main wires *a*, *a'* for a purpose which will be understood. Extending substantially transversely between the opposite main frame wires *a* and *a'* and along a line a little above the eyes of the wearer is the upper eye wire *c*. In the present construction, the lower eye wire *c'* is extended substantially transversely between the main frame members *a* and *a'* along a line a little below the eyes of the wearer, this wire being curved in a manner well known, at 60 points directly below the eyes of the wearer. This lower eye wire *c'* may be either welded to one or both of said frame members *a*, *a'*, or may be formed as an integral part thereof. 65

The main feature of the invention, which resides in the provision of protecting frames for the ears of the wearer, is realized by uniting securely with the main frame wires *a*, *a'*, of the mask frame wire *d* formed to 70 constitute a suitable support for other wires *e*, united likewise with the main frame wires of the mask. The ear protectors formed by the wires *d* and *e* preferably flare rearwardly and outwardly from the main frame 75 wires *a*, *a'*, so as to deflect more readily any balls which may strike thereon. This flaring effect will in turn afford greater protection to the ears of the wearer. It is to be noted particularly that the frame wires *d* of the ear protectors are secured at their lower portions, as at *d'*, *d²*, to the main frame wires *a*, *a'*, and are then bent upward to the front and to the rear to form part of the mask framework proper. Thus, the portions *d²* of the frame wires *d* of the ear protectors extend upwardly across the front of the mask and are united at their ends to the lower eye wire *c'*, thereby strengthening greatly the lower eye wire and the entire mask. In addition, this arrangement of wires serves to eliminate the usual additional wires which extend downwardly from the eye wires to the chin rest portion of the mask. The entire construction illustrated 80 herein thus combines with the desirable features of additional protection the added features of increased strength and simplicity in construction. 85

It has usually been the practice to re- 90

ure the center head strap, indicated at *f*, to some integral portion of the frame of the mask proper. This invention seeks to improve this construction by providing a 5 special wire loop *f'*, separate from the frame of the mask but secured fixedly thereto, to hold the center head strap *f* in its proper position. This loop *f'* may be welded or otherwise secured to any suitable portion 10 of the frame of the mask and not only gives increased strength and additional facility for securing the head strap but improves generally the symmetry and appearance of the mask.

15 The remaining object of the invention now to be considered resides in the provision of a suitable free space in the frame of the mask to permit expectoration by the catcher without the interference of any of the constituent parts of the mask. Such a space is formed in the present embodiment by a wire *g*, bent in an oval and disposed directly in front of but around the line of the mouth of the catcher and united at several 20 points along its periphery with the contiguous frame wires *b'*, *b³*, *b⁴*, *b⁵*, and *b⁶* of the mask. The downwardly extending wires *b'* which are united at one end to the lower eye wire *c'* substantially midway between the 25 main frame wires *a*, *a'* and at their lower ends to the chin wire *b²* form, in this construction, admirable reinforcing members for the oval wire *g*, the latter being secured thereto at substantially diametrical points *g'*. The 30 usual vertical central wire *b³* is broken so as to leave the space within the wire *g* free, although the upper portion of the central vertical wire *b³* is secured at one end to the wire *g* and the lower portion *b⁴* of the central vertical wire is secured to the wire *g* at 35 a point substantially diametrical to the point of attachment of the first named portion *b³*. In the interest of greater rigidity the transverse protecting wires *b⁵* and *b⁶* 40 may be united with the oval bounding wire *g* at points in proximity to the points of attachment of the central vertical wires *b³* and *b⁴*.

45 I claim as my invention:

50 1. In combination with a wire baseball mask including the main frame and the lower eye wire, ear protecting frames composed of bounding wires united with the main frame of the mask and bent to extend

upwardly across the face of the mask and 55 unite with the lower eye wire to reinforce the same, and reinforcing wires united with the main frame of the mask and the bounding wires of the ear protecting frames respectively, the last named frames being 60 formed to flare rearwardly and outwardly from the main frame of the mask.

2. A baseball mask composed of a main frame and face protecting members united therewith to form a protective frame for the 65 face of the wearer, the protective frame being provided with an opening substantially opposite and larger than the mouth of the wearer to permit expectoration without interference.

70 3. A baseball mask composed of a main frame and face protecting members united therewith to form a protective frame for the face of the wearer, one of the protecting members being disposed to protect the 75 mouth of the wearer and formed to provide an opening substantially opposite and larger than the mouth of the wearer to permit expectoration without interference.

4. A baseball mask composed of a main 80 frame and face protecting members united therewith to form a protective frame for the face of the wearer and including a lower eye wire and a chin wire, diverging wires secured adjacent their upper and lower ends to the lower eye wire and the chin wire respectively, a transverse wire extending between and united with the main frame of the mask and disposed along and above the outline of 90 the wearer's mouth, a second wire extending between and united with the lower portions of the divergent wires and a wire bent to form an oval shaped opening disposed directly in front of but around the outline 95 of the wearer's mouth to permit expectoration without interference, said last named wire being united at points substantially on the major axis of the oval outline with said vertical wires and with said transverse 100 wires at points substantially on the minor axis of said oval outline.

This specification signed and witnessed this 19th day of June A. D. 1913.

ROBERT L. WELCH.
